UNITED STATES PATENT OFFICE.

JOB TAYLOR, OF ORCHARD PARK, NEW YORK.

CORN-SIFTER.

SPECIFICATION forming part of Letters Patent No. 298,429, dated May 13, 1884.

Application filed August 11, 1883. (No model.)

To all whom it may concern:

Be it known that I, JOB TAYLOR, of Orchard Park, in the county of Erie and State of New York, have invented certain new and useful 5 Improvements in Corn-Sifters; and I do hereby declare that the following description of my said invention, taken in connection with the accompanying sheets of drawings, forms a full, clear, and exact specification, which will 10 enable others skilled in the art to which it appertains to make and use the same.

My present invention has relation to separators for separating the cobs and silks from green corn after said corn has been removed 15 from the cob; and it consists in the construction and arrangement of parts, as will be hereinafter described, and particularly pointed out in the claims.

In the accompanying drawings, Figure 1 is 20 a side elevation of a corn-cutting machine provided with my improved corn-sifter. Fig. 2 is a front elevation of the corn-sifting device detached. Fig. 3 is a plan view of the corn-sifter and the mechanism for supporting and 25 vibrating the same, the corn-cutter and certain other parts being removed in order to more fully show the details of my improvement. Fig. 4 is an enlarged detail view of the supporting-bar X and the sifter-frame K, partly broken 30 away.

The letter B in Fig. 1 of these drawings illustrates the so-called "Sprague corn-cutter," being a well-known machine for removing the green corn from the cob, A and A' being the frame thereof, as clearly shown in the 35 drawings. This corn-cutter has a series of gear-wheels, C, to operate the feed-wheel, (not shown,) and into one of these gear-wheels I mesh a spur-wheel, D, fixed to one end of an 40 axle or shaft, E, the other one of which is fitted with a crank-disk, F, said shaft being constructed to revolve in bearings G G', fixed to the frame A A' in any suitable and convenient manner. To the wrist-pin f of this crank-disk 45 is fitted one end of a connecting-rod, H, the other end of which is connected to a lever, I, pivoted centrally within a bifurcated support, i, fixed to the frame A, said lever being connected with the sifter-bar L by means of a connection, J, as clearly illustrated in the figures.

The mechanism heretofore described serves

to give a vibratory motion to a sifter-frame, K, pivoted to a supporting-bar, X, which is supported by and suitably secured to the arms M M' by means of pivots x at its inner ends, 55 and adjustably secured to the slotted portions n in the outer ends of the arms M M' of the bar L, the thumb-screws O operating on screw-threaded bolts N of the frame K, whereby the front portion of said frame is raised or lowered 60 in any desired position within the range of said slot-holes n.

The sifter-frame K is provided with a series of lugs, k, upon which rest two sifters, K' K², (shown in Fig. 1,) consisting each of a suitable 65 metallic frame, covered or otherwise fitted with wire-cloth of proper mesh, said frames being retained within said sifter by means of pins d, passing through said lugs k and the frame of the sifters K' K², as shown in Figs. 2 and 3. 70

The sifter-bar L is pivoted at a to the bar T, fixed to the sides of the frame A A', so as to sustain that end of said bar L farthest from the sifter-frame K'. To this sifter-frame are secured two arms, Y, which terminate in pivots y, engaging the supporting-bars R, the lower ends of which are pivoted to lugs S, (shown in Fig. 1,) fixed to the frame A A'. These supporting-bars R carry the frame K, with the sifters K' K², and are so arranged as 75 to vibrate on the pivots in the lugs S. 80

It will be understood that when the corn-cutter is operating motion will be imparted to the machine through belt W, engaging pulley V upon the main shaft U. Such motion is also 85 communicated to the sifting device by the wheels C and D and the mechanism heretofore described.

The corn, with particles of silk and cobs discharging from the apron Z, Fig. 1, drops down 90 into the frame K upon the upper sifter, K'. The corn, being the smallest in size, is permitted to pass through the meshes of sifters K' K², while the cobs or other pieces thereof are retained upon said sifters, together with the 95 silks, the screened corn dropping into a pan, P, placed upon a suitable table underneath the sifters, while the cobs and other matter are discharged from the front portion, K'', of the sieve-frame (shown in Fig. 3) into any suitable and 100 convenient vessel, not necessary to be shown.

As heretofore described, the sifters K' K²

are removably fixed within the frame K, so that whenever a portion of the cobs has accumulated thereupon, having failed to pass out at K" of the sieve-frame, said sifters may be 5 withdrawn and the refuse matter removed from the meshes of said sifters.

Having described my invention, I desire it to be understood that I do not confine myself to the construction of the mechanism employed o for operating the sifters, as I may vary the same without departing from the invention or the true spirit and scope thereof.

What I claim is—

1. The combination, with the frame A A', 5 the arm T, the bar L, pivoted to said arm at a, and having the arms M M', the bar X, the frame K, pivoted at x x to the bar X, and the

sifters K' K², removably secured to said frame, as shown and described.

2. The combination, with the frame A A', 20 the support T, the bar L, having arms M M', provided with slots n, and pivoted at a to support T, the bar X, the frame K, pivoted at x x, the removable sifters K' K², and the thumb-nuts O, for adjusting said frame by means of 25 the slotted arms M M', as set forth.

In testimony that I claim the foregoing as my invention I have hereto set my hand in the presence of two subscribing witnesses.

JOB TAYLOR.
